UNITED STATES PATENT OFFICE.

WILLIAM HENRY SUMBLING, OF TORONTO, ONTARIO, CANADA, ASSIGNOR TO SUMBLING MACHINERY COMPANY, LIMITED, OF TORONTO, ONTARIO, CANADA.

FLUID-TIGHT JOINT.

Application filed June 7, 1920. Serial No. 387,120.

To all whom it may concern:

Be it known that I, WILLIAM HENRY SUMBLING, a subject of the King of Great Britain, residing in the city of Toronto, 5 county of York, Province of Ontario, Canada, have invented certain new and useful Improvements in Fluid-Tight Joints, of which the following is a specification.

My invention relates to improvements in 10 fluid-tight joints, and the object of the invention is to provide a relatively cheap yet positive joint to render vessels of various sorts fluid-tight irrespective of changes in temperature, and more specifically to make 15 the casing of a washing machine watertight, and in the following specification I shall describe the construction of the preferred form of my invention as applied to washing machines, and what I claim as new 20 will be set forth in the claims forming part of this specification.

The drawing is a horizontal longitudinal section through a vessel provided with a water-tight joint made according to my invention. 25

As far as I am aware, no fluid-tight joint has been designed embodying the principle of my joint, (the efficiency of which is not impaired by change in temperature), where- 30 in the end of the body-portion of the vessel co-acts with a sloping wall formed in the inner side of the closure-member therefor, in such a manner as to jam a packing laterally between said body-portion and said 35 closure-member, the force holding the said closure-member and the body-portion in co-operative relationship being exerted longitudinally, transversely, or vertically of the vessel.

40 The end of the body-portion of the vessel will be some distance from the bottom of the groove, and consequently should the packing shrink, the binding means can be adjusted to increase the pressure against the 45 said packing and so keep the joint fluid-tight. The said packing will always be so associated with said closure member that the body-portion will laterally be held in spaced relation thereto; therefore, since the 50 end of said body-portion will be held in spaced relation to the bottom of the groove, or the bottom of said sloping wall, and having in view the spaced relation laterally between the said body-portion and said closure 55 member, the necessary space is provided to

allow for adjustments, which adjustments may be rendered necessary (a) in order to increase pressure against the packing in case the same should shrink, and (b) in case of deterioration of the said end of the body-portion (for instance through the action of rust when said body-portion is made of metal) which would necessarily require adjustment of the elements to exert the necessary pressure against the packing. 60

One very important object resulting from a joint embodying the principle of my invention is that the packing can be readily removed and replaced by fresh packing when occasion requires. 70

When a vessel constructed with a joint embodying the principle of my invention is made of wood, of course the expansion and contraction thereof will be practically negligible, and so consequently the pressure exerted against the packing will be substantially constant. But should the body-portion as well as the closure-member, be made of metal, by reason of the provision allowed for free expansion, there will be no danger 75 of the body-portion buckling, because the end of the body-portion will be free to ride upon the said sloped wall. 80

The preferred form of binding means will be so located that it will practically not be 85 influenced by any change in temperature within the vessel resulting in an advantage well understood by one skilled in the art.

A is the body-portion of the washing machine used as an exemplary means for the 90 disclosure of my invention, and this body-portion is shown as closed by closure-members B and C preferably made of metal.

In my preferred form of joint, I form in the inner side of each closure-members B 95 and C, a groove D having a sloping wall E. The other wall F of the said groove, for cheapness of manufacture, extends preferably longitudinally of the body-portion A, and formed therein is a groove G in which 100 is mounted any suitable packing H which extends preferably beyond the face of the wall F. Each end of the body portion A rides upon the sloping wall E of its associated groove D, and when pressure is exerted longitudinally of the body-portion A, the sloping wall E will compel each end portion of the body-portion A to more or less expand and snugly hug the packing H and 105 keep the same snugly packed within the 110

groove G so as to prevent leakage. It is quite possible that fluid may escape between the sloping wall E and its associated end I of the body-portion A, but such fluid will 5 not escape around the packing H.

The preferred means of holding the body-portion A and the closure-members B and C in co-operative relationship is in the form of tie-rods J which are disposed longitudinally of said body-portion and pass through holes K formed in the said closure-members B and C. Suitable fastening means, preferably in the form of nuts L are threaded on the outer ends of said tie-rods and jam 15 against the closure-members B and C.

Since the ends of the body-portion A do not rest in contact with the bottom 2 of the groove D, it is self-evident that the said ends, co-acting with the sloping walls E will 20 allow for expansion and contraction and yet maintain the joint fluid-tight.

By making the closure-members B and C of metal, the grooves before referred to can be readily turned therein without very 25 much cost.

Obviously a vessel may be constructed embodying the principle of my joint, one end of which may be open.

Various changes in details of construction 30 will readily suggest themselves to one skilled in the art without departing from the scope of my claims.

What I claim is:—

1. The combination of a closure member 35 having an annular groove formed in its inner side so as to provide two opposing walls, one of which is sloped; a packing associated with the other of said walls and projecting therebeyond; a body-portion, having 40 its end resting directly in thrust contact with said sloped wall and in spaced relation to the bottom of said groove, and held in spaced relation to said other wall by said packing; and means exerting pressure to 45 hold said body-portion and closure member in co-operative relationship, so as to cause said body-portion to press with sufficient pressure against said packing.

2. The combination of a closure member 50 having an annular groove formed in its inner side so as to provide two opposing walls, one of which slopes outwardly; a packing associated with the other of said walls and projecting therebeyond; a body- 55 portion, having its end resting directly in

thrust contact with said sloped wall and in spaced relation to the bottom of said groove, and held in spaced relation to said other wall by said packing; and means exerting pressure to hold said body-portion and 60 closure member in co-operative relationship, so as to cause said body-portion to press with sufficient pressure against said packing.

3. The combination of a closure member having an annular groove formed in its 65 inner side so as to provide two opposing walls, one of which is sloped, and the other of which is provided with a groove; a packing held in the groove of said groove-provided wall and projecting therebeyond; a 70 body-portion having its end resting directly in thrust contact with said sloped wall and permanently held in spaced relation to said other wall by said packing; and means exerting pressure to hold said body-portion and 75 closure member in co-operative relationship, so as to cause said body-portion to press with sufficient pressure against said packing.

4. The combination of a pair of closure-members each provided with a groove on its 80 inner side each having an inner outward sloping wall, and a grooved wall facing said sloping wall; a body-portion having its ends placed in said grooves directly in thrust contact each with its associated sloping wall; a 85 packing in the groove formed in said other walls and located between said closure-members and the side of said body-portion; the said sloping walls when said closure-members and body-portion are held in co-operative 90 relationship outwardly displacing the said ends so as to jam said packing in place, and tie-rods mounted in said closure-members and adapted to hold the same and said body-portion in co-operative relationship, 95 for the purpose specified.

5. The combination of a closure member having a sloping surface on its inner side, and adapted to carry a suitable packing; a body-portion having its end resting directly 100 in thrust contact with said surface, and laterally contacting with said packing, which packing holds said body-portion laterally in spaced relation to said closure member, and means exerting pressure to hold said 105 body-portion and said closure member in co-operative relationship, for the purpose specified.

WILLIAM HENRY SUMBLING.
